BEAM CLAMP

Raymond L. Martz, Palatine, Ill., assignor to Minerallac
Electric Company, Chicago, Ill.

Filed June 26, 1972, Ser. No. 247,927

Term of patent 14 years

Int. Cl. D8—08

U.S. Cl. D8—235

FIG. 1 is a perspective view of a beam clamp embodying my design shown in place on a supporting structure shown in broken line for illustration purposes only.

FIG. 2 is a top plan view of the beam clamp shown in FIG. 1.

FIG. 3 is a front elevational view of the beam clamp shown in FIG. 1.

FIG. 4 is a side elevational view of the beam clamp shown in FIG. 1.

FIG. 5 is a rear elevational view of the beam clamp shown in FIG. 1.

I claim:

The ornamental design for a beam clamp, as shown and described.
